UNITED STATES PATENT OFFICE

CHESTER L. DAVIS, OF KEOKUK, IOWA, ASSIGNOR TO WIRED RADIO, INC., OF NEW YORK, N. Y., A CORPORATION OF DELAWARE

TELEVISION SYSTEM

Application filed July 3, 1930. Serial No. 465,703.

My invention relates broadly to television systems and more particularly to an image reproducing receiving circuit for television systems.

5 One of the objects of my invention is to provide a receiving circuit for a television system having means for modulating a luminously responsive screen at a receiver according to incoming television signaling energy 10 for the reproduction of an image.

Another object of my invention is to provide a television receiving circuit including a luminously responsive screen adapted to reproduce television signalling energy according 15 to the movement of a potential node along the screen wherein circuits are provided for normally activating the image reproducing screen and modifying the luminous discharge thereof according to variations in the incoming 20 television signaling energy.

My invention is directed to that class of television systems shown more fully in my Letters Patent No. 1,756,086, dated April 29, 1930, entitled "Signaling system", and shown 25 in my application Serial No. 299,501, filed August 14, 1928, entitled "Glow discharge device", now Patent No. 1,789,219, dated Jan. 13, 1930, application Serial No. 414,957, filed December 18, 1929, entitled "Television system", and application Serial No. 434,777, 30 filed March 10, 1930, entitled "Transmission system". For a further understanding of the television system of my invention reference is made to my copending application Serial 35 No. 460,760, filed June 12, 1930, entitled "Television system".

My present invention will be more fully understood from the specification following by reference to the accompanying drawings, 40 in which:

Figure 1 is a diagrammatic circuit arrangement of a television system embodying the principles of my invention; Fig. 2 is a modified circuit arrangement of a television system embodying the principles of my invention; and Fig. 3 is a diagrammatic illustration 45 of a television transmitter.

Referring particularly to Fig. 1, a receiving circuit has been illustrated as comprising 50 antenna 1 connected to ground through the

primary winding 2 of a coupling transformer which has a secondary winding 3 connected to the first stage of radio frequency amplification indicated at 4. A second stage of radio frequency amplification is indicated at 5. The input circuits of each of the radio frequency amplifier stages are aperiodically tuned by virtue of the characteristics of the coupling transformers 30 and 31 in connection with the shunt condensers 32 and 33. 55 The output coupling transformer 6 connects to a synchroscope circuit designated generally at 7. The synchroscope circuit comprises fixed windings 13 and 14 connected in series and energized by constant frequency oscillator 15 controlled by piezo electric crystal element 35. The movable windings 8 and 9 of the synchroscope 7 are connected in separate dephasing circuits containing impedances 10 and 11 in series with winding 9 and inductance 12 in series with winding 8. The movable windings 8 and 9 are arranged in predetermined angular positions and are connected through link 16 with variable condenser 17 which is disposed in circuit with an oscillator 18. The oscillator 18 includes input circuit 19 and output circuit 20. The image reproducing screen which is described more fully in my copending application Serial No. 299,501, filed August 14, 1928, is connected in circuit with the oscillator 18 in such manner that the glow discharge which takes place within the enclosing envelope 36 is normally at uniform intensity throughout the 70 length of the turns of the inductance 21. The condenser 17 which is connected in circuit with the inductance 21 and in circuit with the oscillator 18 as shown when in normal position does not vary the intensity or position 75 of illumination on the screen 21. However, when condenser 17 is varied due to movement of the synchroscope windings 8 and 9 in proportion to the change in frequency over the frequency band which is passed by the substantially aperiodic circuits 30-32 and 31-33 will control the position of the node. The luminous discharge of screen 21 is modulated by impressing received signaling energy 80 from conductors 22 across a part of the oscillator circuit as indicated at condenser 23. 85

The modulation of oscillator 18 by the received signaling energy may be accomplished in any manner well known to those skilled in the art. The potential drop along impedance 10 is transferred along conductors 22 across the condenser 23 thus controlling the intensity of the glow discharge at a potential node which moves along screen 21 according to the capacity variation of condenser 17 for the 10 reproduction of an image.

In the circuit illustrated in Fig. 2, I have shown means for eliminating a constant frequency oscillator at the receiver and employing in lieu thereof the standard source of sixty cycle alternating current lighting energy which is connected to leads 29 and passes through series connected windings 13 and 14 of the synchroscope. The energy which is passed through windings 8 and 9 of the synchroscope 7 in this modification is of an audio frequency inasmuch as I provide a detector 25 connected to the frequency band responsive circuits 30—32 and 31—33. An audio frequency amplifier consisting of power amplification stages 26 and 27 connect to the output of detector 25. The output of audio frequency transformer 28 connects to the circuits of the synchroscope. In this arrangement the television transmitter, shown diagrammatically in Fig. 3, is modulated plus and minus sixty cycles, and as the modulation varies at the receiving station, condenser 17 in Fig. 2 which is connected in the oscillator circuit 18, is automatically shifted through mechanical linkage 16 and the potential along conductors 22 is varied for correspondingly controlling the movement and intensity of a potential node along the luminous discharge screen 21. The transmitter circuit in Fig. 2 is similar to the television circuit set forth in my Letters Patent 1,756,086 except that the oscillator is subjected to constant modulation by the 60 cycle oscillator or lighting line circuit indicated at 37. The television scanning disc is represented at 38 operating to activate photo cell 39 according to the object 40 for correspondingly controlling the modulation of the transmitter under the influence of the photo cell 39. The television signaling energy is emitted over a predetermined recurring frequency band by the coordination of the tuning means 41 in the transmitting circuit with the operation of the scanning disc 38.

It will be seen that the incoming signaling energy in both circuit arrangements of my invention serves to control the effects of the oscillator 18 upon the luminous discharge tube 21. Due to rapidity in movement of potential nodes along the luminous discharge screen, the visual effects are integrated and the persistence of vision of the eye of an observer results in the visual reproduction of the image of the object which is scanned at the distant transmitter.

It will be understood that changes in frequency of the incoming television signaling energy cause displacement of windings 8 and 9 of the inductive synchroscope due to the reaction with the constant magnetic field of predetermined frequency set up by windings 13 and 14. Changes in frequency serve to angularly shift coils 8 and 9 with respect to the fixed windings 13 and 14 thereby shifting the position of condenser 17 through the 75 movement of link 16. Accordingly, the position of a potential node along screen 21 is directly controlled by movement of condenser 17 which changes the frequency of the energy from oscillator 18 which is applied to the inductive screen 21. At the same time the variation in intensity of the received signaling energy through circuit 22 modulates oscillator 18 thereby decreasing or increasing the brilliancy of the various potential nodes set up along the inductance 21 for the 80 reproduction of an image.

While I have described my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. In a television system, means for receiving television signaling energy over a variable frequency range, an inductance constituting a glow discharge screen, means in circuit with said screen for normally energizing said glow discharge screen for producing a predetermined optical effect thereon, and means operated by the incoming signaling energy for changing the frequency response characteristics of said glow discharge screen and simultaneously modulating the energy in circuit with the glow discharge screen according to variations in the incoming signaling energy.

2. A television system comprising a receiving circuit responsive to variable frequency signaling energy, a glow discharge screen connected with said circuit for variably responding to changes in incoming signaling energy, means for independently energizing said glow discharge screen and a variable impedance disposed in circuit with said screen, said impedance being controllable according to changes in frequency of the incoming signaling energy for controlling the potential distribution along said screen thereof according to the variations of incoming signaling energy.

3. In a television system, a signal receiving circuit responsive to variable frequency signaling energy, a glow discharge screen comprising an inductance, means for impressing energy on said glow discharge screen according to changes in incoming signaling energy,

and separate means for energizing said glow discharge screen in proportion to frequency changes in the incoming signaling energy.

4. In a television system, a receiving circuit responsive to changes in incoming signaling energy over a predetermined frequency band, an inductance constituting a glow discharge screen, means for energizing said glow discharge screen for producing a predetermined optical effect thereon, connections for varying the energization of the inductance constituting said screen according to variations in intensity of the incoming signaling energy, and separate means connected with said receiving circuit for controlling the position of maximum luminosity of said glow discharge screen according to changes in frequency of the incoming signaling energy.
5. In a television system, a receiving circuit responsive to a variable range of frequencies, a screen constituted by an inductance, means for impressing incoming television signaling energy on said screen, independent means for normally exciting the inductance constituting said screen for producing a predetermined optical effect thereon and a variable impedance device connected in circuit with the inductance constituting said screen and controlled by said receiving circuit for shifting the position of a potential node along said screen according to changes in frequency of the incoming signaling energy.
6. In a television receiving system, a receiving circuit responsive to a predetermined band of frequencies, an inductance forming an image reproducing screen, means for normally exciting said inductance for producing a predetermined optical effect thereon, and means connected in series with said screen and controlled by the received television signaling energy for varying the excitation of the inductance constituting said screen according to changes in frequency of the incoming signaling energy.
7. In a television receiving system, a receiving circuit responsive to a variable range of frequencies, an inductance comprising an image reproducing screen connected with said receiving circuit, an oscillator for normally exciting said inductance independently of said receiving circuit for producing a predetermined optical effect upon said screen, an angularly shiftable device controlled by said receiving circuit and connected with said screen for variably controlling the excitation of said screen according to changes in frequency of the incoming signaling energy.
8. A television receiving system comprising a receiving circuit responsive to a predetermined band of frequencies, an image reproducing screen constituted by an inductance, an oscillator connected with said inductance for normally exciting said inductance and producing a predetermined optical effect thereon, frequency responsive means operative within the range of frequency covered by said receiving circuit, a variable impedance element controlled by said frequency response means and connected in circuit with said inductance and operating to vary the position of a potential node along said screen according to changes in frequency of the incoming signaling energy.
9. In a television system, a receiving circuit responsive to a predetermined band of frequencies, an image reproducing screen constituted by an inductance connected with said receiving circuit, an oscillator connected with said inductance for normally exciting said inductance and producing a predetermined optical effect thereon, means for controlling the amplitude of excitation according to the amplitude of the received signaling energy, a motor device driven by the incoming signaling energy, a variable impedance connected in circuit with said inductance and angularly shiftable by said motor device, said impedance operating to control the movement of a potential node along said inductance according to the frequency of the incoming signaling energy for producing an optical effect representing the character of the received signaling energy.
10. A television system including a receiving circuit responsive to a predetermined band of frequencies, an image reproducing screen in the form of an inductance connected with said circuit, an oscillating circuit connected to said inductive screen for producing a predetermined glow discharge thereon, an adjustable element in said oscillating circuit, means controlled by changes in frequency of the incoming signaling energy for variably controlling the adjustment of said element for correspondingly modulating the glow discharge on said screen and controlling the movement of potential node along said inductive screen, and connections between said oscillating circuit and said receiving circuit for controlling the intensity of energy supplied to said inductive screen according to the amplitude of the received signaling energy for optically reproducing the character of the received signaling energy.
11. A television receiving system, comprising a receiving circuit responsive to variable frequency television signaling energy, an output system connected with said receiving circuit including an impedance element and an angularly movable inductance device, a stationary inductance device disposed in coacting magnetic relation to said angularly movable inductance device and energized by a constant frequency source of oscillations, an image reproducing screen consisting of a glow discharge inductance, an oscillating circuit connected with said

- glow discharge inductance for subjecting said glow discharge inductance to a predetermined optical effect, connections from said impedance element to said oscillating circuit,
15 a variable tuning element interposed in circuit between said oscillating circuit and said glow discharge inductance, a mechanical connection between said angularly movable inductance device and said variable tuning element for changing the frequency response characteristic of said glow discharge inductance in relation to the change in frequency of the incoming signaling energy and modifying the optical effect reproduced by said screen.
12. A television receiving system, comprising a receiving circuit responsive to variable frequency television signaling energy, an output system connected with said receiving circuit including a resistance member and an angularly movable inductance device, a stationary inductance device disposed in coacting magnetic relation to said angularly movable inductance device and energized by a constant frequency source of oscillations, an image reproducing screen consisting of a glow discharge inductance, an oscillating circuit connected with said glow discharge inductance for subjecting said glow discharge inductance to a predetermined optical effect, connections from said resistance member to said oscillating circuit, a variable tuning element interposed in circuit between said oscillating circuit and said glow discharge inductance, a mechanical connection between said angularly movable inductance device and said variable tuning element for changing the frequency response characteristic of said glow discharge inductance in relation to the change in frequency of the incoming signaling energy and modifying the optical effect reproduced by said screen.

In testimony whereof I affix my signature.
